CLAIM

The ornamental design for a charging case, as shown and described.

DESCRIPTION

FIG. 1 is a top, front and right side perspective view of a charging case showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an alternative view of the charging case with its cover open.

The broken lines are shown for the purpose of illustrating part of the article that form no part of the claimed design.

1 Claim, 9 Drawing Sheets
